US00D936019S

(12) **United States Design Patent** (10) Patent No.: **US D936,019 S**
(45) Date of Patent: **** Nov. 16, 2021**

(54) **WALL ADAPTER**

(71) Applicant: **DESIGN POOL LIMITED**, Wanchai (HK)

(72) Inventor: **Igor Raymond Antoine Duc**, Sai Kung (HK)

(73) Assignee: **DESIGN POOL LIMITED**, Wanchai (HK)

(**) Term: **15 Years**

(21) Appl. No.: **29/711,275**

(22) Filed: **Oct. 30, 2019**

(30) **Foreign Application Priority Data**

Apr. 30, 2019 (HK) 1913558.9M

(51) LOC (13) Cl. **13-02**

(52) U.S. Cl.

USPC **D13/137.2; D13/110; D13/138.1**

(58) **Field of Classification Search**

USPC D13/137.1–137.4, 138.1, 138.2,

D13/139.1–139.8, 146, 147, 154, 158,

D13/171, 173, 174, 184, 107, 108, 110;

D14/432, 433

(57) **CLAIM**

The ornamental design for a wall adapter, as shown and described.

DESCRIPTION

FIG. 1 is a front view of a wall adapter;

FIG. 2 is a back view of the wall adapter;

FIG. 3 is a left view of the wall adapter;

FIG. 4 is a right view of the wall adapter;

FIG. 5 is a top plan view of the wall adapter;

FIG. 6 is a bottom view of the wall adapter; and,

FIG. 7 is a perspective view of the wall adapter.

The broken lines in the drawings depict portions of the wall adapter that form no part of the claimed design.

1 Claim, 7 Drawing Sheets
